UNITED STATES PATENT OFFICE.

FERDINAND J. SPANG, OF BUTLER, PENNSYLVANIA, ASSIGNOR TO SPANG AND COMPANY, OF BUTLER, PENNSYLVANIA, A CORPORATION OF PENNSYLVANIA.

WELL PLUG.

Application filed January 9, 1926. Serial No. 80,232.

This invention relates to deep well tools for use in connection with oil wells or the like and more particularly to the so called well hole plugs such as are commonly used 5 for plugging the bottom of a well hole for the purpose of stopping the seepage of water into the well through crevices in the bottom wall when the well has been driven into a water stratum.

10 Heretofore, such tools have usually consisted of a cylindrical plug of soft metal such as lead having a tapered mandrel projecting upwardly from the top. The plug and mandrel are lowered to the bottom of the 15 well hole and the mandrel is then driven into the plug by a downward jarring so as to expand the soft metal and force it into such contact with the wall as to plug the bottom of the well and stop the seepage of 20 water into the well.

This type of well plug has long been in use but is not entirely effective, due to the inability of forcing soft metal into such intimate contact with the walls of the well 25 and the crevices therein, as to form a positive water seal; and an object of this invention is to provide an improved form of well plug of such construction and arrangement as to insure a closing of the bottom of 30 the well and a positive sealing of all crevices therein.

A further object of this invention is to provide a device of the type set forth having 35 means for closing or shutting off the well above the plug.

A still further object is to provide a well plug which will be relatively cheap to manufacture, easy to manipulate and positive in 40 operation.

45 These and other objects which will be obvious to those skilled in this particular art are attained by means of this invention, one form of which is illustrated in the accompanying drawing, in which Figure 1 is a longitudinal sectional view through a well plug constructed in accordance with one 50 form of this invention. Fig. 2 is a plan view of the plug proper with the expanding mandrel removed. Fig. 3 is a sectional plan view 55 of a well hole diagrammatically showing a crevice to be sealed and Fig. 4 is a vertical sectional view thereof.

The illustrated embodiment of this invention includes a cylindrical plug 5 which is 60 preferably formed of relatively soft, mallea-

ble metal such, for example, as lead and which is provided with a series of circumferential grooves 6 having rings or annuli 7 embedded therein. These annular members are preferably formed of some material, such 60 as crude or partially vulcanized rubber or the like which is soft and adapted to flow easily under pressure.

A mandrel 8 has a serrated end 9 positioned in a bore 10 formed at one end of the 65 metal plug. The mandrel projects above the plug and has a tapered surface 10 which diverges toward its upper end. A plurality of split rings or washers 11 are positioned on the end of the plug 5 around the mandrel 70 and are so positioned relatively to one another that the splits 11' are in staggered relation. The mandrel has a hook 12 or similar device by which it may be wired to the string 75 of tools.

Assuming that a well 13 has been drilled through the oil bearing stratum and has penetrated to a level where water seeps into the bottom of the well hole through crevices 14, the well plug is secured to the end of a string 80 of tools by a relatively small wire 15 or the like and lowered into position at the bottom of the well hole. The mandrel 8 is then driven downwardly through the plug by downward jarring of the tools. Driving the tapered section 10 of the mandrel into the plug causes the latter to spread or expand outwardly and to be pressed against the wall of the well hole with considerable pressure. The soft annular inserts 7 will flow more readily 85 than the metal and be forced more effectively into the adjacent crevices of the wall so as to effectually close the same and stop the seepage of water therefrom. Driving the mandrel into the plug also causes the split rings 90 11 to be expanded outwardly as indicated in dotted lines in Fig. 2, so that they are forced laterally into the wall to close the well hole above the plug and seal the upper end of the space or joint between the plug and the wall 95 of the hole so that no fluid can pass upwardly around the outer surface of the well plug. Each insert 7 not only closes all crevices with which it is brought into association but also forms an effective seal against the upward 100 passage of water along the surface of the plug 5 because the expansion of the plug will cause the insert 7 to swell and flow outwardly 105 beyond the surface of the leaden plug itself.

The wire 15 is broken by the downward 110

jarring of the tools so that the latter can readily be withdrawn from the well.

What I claim as new and desire to secure by Letters Patent is:

- 5 1. The combination in a well plug of an elongated body portion of malleable metal provided with a plurality of grooves in the outer face thereof, inserts of readily flowing rubber mounted in said grooves and a tapered mandrel for expanding said body portion and said inserts.
- 10 2. The combination in a well plug of a ta-

pered mandrel for expanding said plug on downward jarring and a plurality of split washers surrounding said mandrel on top of 15 said plug so as to be expanded by movement of said mandrel relatively thereto, said washers being so positioned relatively to one another that the splits thereof are in staggered relation.

In testimony whereof, I have hereunto subscribed my name this seventh day of January, 1926.

FERDINAND J. SPANG.
